UNITED STATES PATENT OFFICE.

FREDERICK S. DENISON, OF MINNEAPOLIS, MINNESOTA, ASSIGNOR TO MINNEAPOLIS
HEAT REGULATOR COMPANY, OF MINNEAPOLIS, MINNESOTA, A CORPORATION OF
MINNESOTA.

CENTRIFUGAL FLUID-FUEL BURNER.

Application filed March 24, 1924. Serial No. 701,480.

This invention relates to improvements in fluid fuel burners of the centrifugal type for the circumferential distribution of fluid fuel such, for example, as are known in the oil-burning art. More particularly, this invention relates to such burners of the general type disclosed in applicant's prior co-pending application Serial No. 698,109, filed March 10, 1924. In both cases, there is provided a burner of a compact unitary structure which is quiet and efficient in operation, the power consumption is minimized, the moving parts are few and not liable to derangement and may be conveniently balanced statically and dynamically with resultant minimizing of destructive vibrations and attendant noise.

In the prior case, the fuel was forced from the fuel chamber by a pump through a conduit which extended through a shaft to the distributing head. In the present case, the shafting may be solid and the conduit is provided outside the shafting and extends from the pump to the head and a valve may be interposed in the conduit at a conveniently accessible place to regulate the fuel passage. While the structural alignment of the axes of the head, motor and pump are preferably retained in this present burner, it may be noted that the lower bearing housing for the shafting is borne by the fuel chamber in the present burner as distinguished from the bearing shown in the prior application.

The object of this invention is to provide an improved fluid fuel burner of the centrifugal type.

Other objects of the invention will more fully appear from the following description and the accompanying drawings and will be pointed out in the annexed claims.

In the drawings there has been disclosed a structure designed to carry out the objects of the invention, but it is to be understood that the invention is not confined to the exact features shown, as various changes may be made within the scope of the claims which follow.

In the drawings:

Figure 1 is a vertical sectional view through the burner with the motor shown in full lines;

Figure 2 is a cross-sectional view on the line 2—2 of Figure 1; and

Figure 3 is a cross-sectional view on the line 3—3 of Figure 1.

In the form of the invention disclosed in the drawings, there is illustrated a centrifugal burner of the upright type although with minor changes in bearings, packing, etc., the burner may be used at different angles to the horizontal or vertical.

The major parts of the structure are the distributing head, the shafting, the driving means (for example an electric motor), the pumping means and the conduit leading from the pumping means to the head.

The shafting 4 is preferably an integral structure although it may be made in two or more parts in axial alignment for simultaneous actuation by the driving motor 5. While the motor may be supported upon the floor or other base 6, it is shown as supported by the legs 7 upon the cover 8 of the casing 9 which forms the chamber for reception of fuel such as the usual oil 11. The rotor of the motor is fixed in accordance with common practice to the shafting for actuation of the latter and bearings may be provided by the motor therefor as is common. A bearing for one end portion of the shafting may be provided by the bearing housing 12 which may be carried by the chamber. As here shown such housing 12 is shown as integrally cast with the metal of the chamber cover 8. For convenience of terminology, this end portion of the shafting may be called the inner while the opposite end portion may be referred to as the outer.

The distributing head is mounted upon the shafting adjacent the outer end thereof. The head comprises a cap 13 and a channelled member 14. The cap is fixed to the reduced end 15 of the shafting and is adapted to rotate therewith. The channelled member 14 is substantially saucer-shaped with an inner annular channel 16, the inner side 17 of which is outwardly turned in substantial parallelism with the axis of the shafting and spaced therefrom to admit therebetween a pipe or other conduit for the supply of fuel to the distributing head. This channelled member 14 is supported from the cap 13 by means of a plurality of threaded bolts 18 extending through the cap and received in threaded engagement within recesses in lugs 19 integral with the channelled member 14.

The chamber casing 9 is preferably of

metal shaped in the form shown to provide an upper offset recess which is utilized as a float-chamber 21 for the valve and float 22 which automatically regulates the level of the oil in the chamber casing 9 in the usual manner. The oil-supply is received by the pipe 23, from a source not necessary to be shown, and after passing the float valve enters the float and main chambers.

10 The pumping means is here shown as of the centrifugal variety and comprises a plurality of vanes 24 radially extending from a hub 25 fixed to the reduced end 26 of the shafting and adapted to rotate therewith. These vanes which are shown as four in Figure 2 extend between two disks, an upper and a lower. Each of these disks is carried by the hub 25. As here shown, the lower disk 27 is integral with the hub and extends with its peripheral edge in relatively close proximity to the inner face of the skirt 28 annularly depending from the bearing housing 12. The upper disk 29 may be a separate member but is fixedly secured to the hub and spaced from the lower disk so that the under face of the disk 29 abuts against the upper edge of the vanes 24. These two disks and vanes rotate as a unit, and the upper disk 29 is of less diameter than the lower disk 27. In operation, the oil 11 enters between the rotating vanes by means of the apertures 31 in the lower disk and is outwardly thrown by the vanes to pass upwardly beyond the upper disk 29. Preferably a third disk 32 is mounted above the upper rotating disk 29 in proximity thereto. This disk 32 is stationary and functions to overcome any tendency of the centrifugally forced oil to churn idly above the upper disk. The stationary disk 32 is preferably secured to the lower end of the axially depending annular shoulder 33 of the bearing housing 12. A conduit is provided for the passage of the forced oil from the pumping means to the distributing head. This conduit traverses the bearing housing, an offset neck with interposed valve, and the piping. The bearing housing 12 is provided with a plurality of outwardly and axially inclined borings to form the passages 34 leading from the interior of the skirt 28 above the pump disks to an annular groove 35 in the housing. The groove communicates with an outwardly inclined passage 36 axially bored in an elongated neck 37 which may be cast integrally with the housing 12. This passage 36 extends through the outer end of this neck and is threaded to receive in adjustable engagement a needle valve 38 which may be held in the desired position by means of the lock-nut 39. A relatively short boss 41 is also formed upon the outer portion of the neck at an angle to its axis. This boss is also bored to provide a pas-

sage 42 communicating with the neck-passage 36 so that the position of the valve 38 may control the movement of oil through these passages. The boss is counterbored and threaded to receive the end of the pipe section 43 which outwardly extends around the motor 5 and may be held thereto by the bracket 44. From the bracket this section 43 is preferably inclined toward the shafting and thereafter extends in substantial parallelism therewith through the space between the shafting and the inner side 17 of the channeled member. A recess for packing 45 is formed in the housing 12 and a packing nut 46 is received in threaded engagement therein.

In operation of the burner, the motor is energized to rotate the shafting which both rotates the distributing head and the pumping means. Oil, which is maintained at a constant level in the chamber, enters the apertures 31 in the lower rotating disk and is radially thrown by the vanes 24 to pass beyond the stationary disk 32 whence it seeks its outlet by the passage 32 to the annular groove 35 then to the passage 36 through the valve 38, if open, to the pipe section 43 from the outer end of which the oil is discharged to the channel 16 of the head. Head-rotation develops the centrifugal force which causes the oil to travel over the inclined inner face of the channeled member 14 and to be circumferentially distributed in a combustible form between the peripheral lips of the cap 13 and the channeled member 14.

Having thus described my invention what I claim as new and desire to secure by Letters-Patent, is:

1. A device of the class described comprising a reservoir base, having a bearing in its top wall extending within the reservoir, a motor mounted above the reservoir base having a vertical shaft rotatable in the bearing, a hollow burner head upon the shaft having a vertical flange defining an opening encircling the shaft, a conduit communicating with the reservoir, leading through said bearing and including a pipe extending freely through the opening of the burner head to deliver at the inner side of the vertical flange and within the head, and a pump within the reservoir base rotatable by a shaft and adapted to deliver oil through the conduit.

2. A device of the class described comprising a reservoir base provided with a bearing extension in its top wall, said extension having a terminal chamber within the reservoir and further having an upwardly extending passage communicating with the terminal chamber, a motor above the reservoir having a shaft rotatable in the bearing extension, a hollow burner head upon the shaft above the motor having a flange defining an orifice

- freely encircling the shaft, a pipe communicating with the extension passage, and passing freely through the burner head orifice, and arranged to discharge downwardly at 5 the inner side of the flange within the head, and a disc pump within the terminal chamber adapted to discharge into the extension passage.
3. A device of the class described comprising a reservoir base having a cover provided with a hub having a terminal chamber within the reservoir opening downwardly, a motor supported upon the cover and having a shaft extending through the hub and chamber, a stationary disk attached horizontally to the hub within the chamber, spaced disks secured to the shaft below and parallel with said stationary disk, with the bottom disk substantially close to the lower open side of 10 the chamber, and having radial ribs and openings therebetween, a centrifugal burner head rotatable with the shaft and having a
- central flanged opening encircling the shaft, a fuel-delivery conduit extending through the hub and laterally of the motor, and a pipe communicating with said conduit and extending freely through the flanged opening of the burner head to deliver oil therewithin.
4. A centrifugal fluid fuel burner, including a reservoir base, a motor supported upon the base and having a shaft, a rotatable burner head on the shaft above the motor, arranged for horizontal distribution of the fuel in sheet form, disk fuel-pumping means 35 on the shaft below the motor within the reservoir, and a fuel conduit communicating with the pumping means, and leading upwardly and outwardly therefrom around the motor to discharge downwardly within the 40 burner head.

In witness whereof, I have hereunto set my hand this 4th day of March, 1924.

FREDERICK S. DENISON.
